DESCRIPTION

U.S. PATENT DOCUMENTS

FIG. 1 is a top perspective view of a screwdriver, showing my new design.

FIG. 2 is a bottom perspective view thereof.

FIG. 3 is a left side elevational view thereof.

FIG. 4 is a right side elevational view thereof.

FIG. 5 is a rear elevational view thereof.

FIG. 6 is a front elevational view thereof.

FIG. 7 is a top plan view thereof; and,

FIG. 8 is a bottom plan view thereof.

Stippling in the drawings represent the three-dimensional contours of the design, and is not intended to indicate surface decoration. The broken lines shown in the drawings depict portions of the screwdriver that form no part of the claimed design.
